CATHODE RAY TUBE

Otto Baier, Berlin, Germany, assignor to C. Lorenz Aktiengesellschaft, Berlin-Tempelhof, Germany, a company

Application February 23, 1938, Serial No. 192,047
In Germany February 22, 1937

4 Claims. (Cl. 250—141)

(Granted under the provisions of sec. 14, act of
March 2, 1927; 357 O. G. 5)

The present invention relates to cathode ray tubes, and particularly to improvements with respect to the supporting means for the cathode and the control electrode of such tubes.

5 The relative adjustment of the cathode and the control electrode is of utmost importance in making cathode ray tubes, since the correct distance between the glowing cathode and the control electrode or Wehnelt cylinder determines the 10 characteristic of the tube. In serially manufacturing cathode ray tubes particularly for television purposes, it is most desirable that each individual tube has substantially the same characteristic. The known constructions of cathode 15 ray tubes having a glowing cathode are rather disadvantageous in this respect. The physical support of the cathode generally consists of one single lug which simultaneously acts as lead-in conductor. It has, therefore, been necessary in 20 each case to subject the cathode to special adjustment, a requirement which has not been conducive to facilitate the manufacturing process. In addition, this type of support suffers under a considerable lack of stability and is, therefore, subjected to changes on heating the tube, or under the influence of mechanical vibrations.

These disadvantages are obviated according to the present invention which proposes the cathode to be fixedly mounted in a supporting member, 30 whereupon this combined body is attached in a press fit fashion to a hollow cylinder mounted in the center of the electrode system of the tube.

The invention will be more readily understood from the following description taken in conjunction with the accompanying drawing, in which—

Fig. 1 shows a cross section through a new electrode assembly according to the invention; Fig. 2 is a bottom view of the arrangement shown in 40 Fig. 1; while Fig. 3 illustrates a cross section through a further modification of the inventive idea.

Referring to Figs. 1 and 2, reference numeral 1 indicates an insulating body, e. g., of a ceramic 45 material. This body has a central bore, the upper portion of which is flared. The cathode 2, which in this embodiment is assumed to be a small nickel tube, the upper end of which is closed so as to form a surface for the electron emitting substance, while its lower end presents reduced diameter by means of a conical portion, is inserted into the bore of the insulating body 1. The flared portion of this body serves as a seat 50 for the conical portion of the cathode 2, so as to

compulsorily secure a given position of the electron emitting surface 4 with respect to the base surface of the insulating body 1. The lower end of the nickel tube is turned over the bottom surface of the insulating body 1 in order to secure 5 rigid connection. The cathode is heated by means of a heating coil. One of the cathode leads 3 is placed within the nickel tube, while the second lead 3 extends through a particular hole 5 provided in the insulating body 1. The upper portion of the insulating body 1 is provided with a groove which serves as a seat for a metal cap 6. The position of this metal cap with respect to the emitting surface of the cathode is thus given by said groove, so that there is no 10 necessity for any kind of adjustment of this distance which is most significant for the tube characteristic. The outer surface of the insulating body carries a longitudinal slot 7 through which a lug 8 of the cap 6 is extended to the lower end 15 of the body 1. This body together with the cathode 2 and the control electrode 6 is inserted in press fit fashion in a holding member located in the center of the electrode system. Only the essential parts of this system, i. e., the supporting 20 rods 9, the concentrating cylinder 10 with its diaphragm 11, are indicated in Fig. 1. The holding member is shown as a hollow cylinder 12 which is fixed to the electrode system by clamp rings, 25 for example, or by means of a number of discs 13 as shown in Fig. 1, so as to obtain concentric position thereof with respect to the diaphragm 11. The coaxial relation of the cathode 2 and the diaphragm 14 of the control electrode 6 to the 30 lens diaphragm 11 and the metal cylinder 12 is thus compulsorily given, so that merely an axial 35 adjustment is required. This adjustment is accomplished by the agency of the lug 8 which is bent over the cylinder 12 and attached to the disc 13 by welding, for example. This arrangement 40 provides reliable contact between the cap 6, and the cylinder 12, so that the effective area of the control electrode is still increased by the hollow cylinder 12.

45 A further modification of the inventive idea is shown in Fig. 3. The cathode 2 is carried by an insulating tube 15 through which the two lead-in conductors 3 extend. The insulating tube 15 is placed in a support 1 of very low heat conductivity, e. g., Invar steel. This support is provided with a shoulder 16. A disc-shaped diaphragm 17 which is mounted in any manner in the center of the electrode system carries a hollow cylinder 18 attached to its lower face by welding, for in- 50 55

stance. This hollow cylinder is adapted to receive the metallic support 1 and the cathode 2 attached thereto. On inserting the last mentioned unit, the shoulder 16 serves as a detent so as to secure a predetermined axial interspace between the emitting face of the cathode and the adjacent electrode thereof. The hollow cylinder 18 and the disc-shaped diaphragm 17 conjointly serve as control electrode or Wehnelt cylinder. 5 In contradiction to the first embodiment, this modification employs a supporting member which is maintained at the same potential as the control electrode from which follows that the cathode must be insulated from the metallic support 1. 10

Referring for instance to the arrangement first described, the cap of the control electrode may be fixed to the open ended hollow cylinder carrying the insulating body, instead of being fixed to this body. On the other hand the reverse of the above mentioned possibility may be applied to the second modification, that is to say to provide the metallic support with a cap and to enlarge the diaphragm of the disc 17. It is thus obvious that the invention is by no means limited to the structures heretofore described and demonstrated merely by way of examples. 20

The cathode thus shown is unmovably fixed in a supporting member which is in turn inserted in a hollow cylinder fixed in the center of the electrode system. A structure of perfect stability is thereby obtained, so that the cathode will remain unaffected by whatever vibrations may occur. 25 Since the cathode is mounted in a supporting member located externally with respect to the electrode system, the above mentioned adjusting process becomes very simple, so that no expertness is required for accomplishing this adjustment. In cases of a repair, a damaged cathode may easily be replaced by another cathode merely by removing the supporting member. 40

What is claimed is:

1. A cathode ray tube comprising a cathode, a supporting means of insulating material therefor, a hollow cylinder in which said supporting means is slidably positioned, said cylinder being of such diameter as frictionally to hold said supporting means, whereby the position of said cathode with respect to said cylinder may be readily adjusted, a diaphragm electrode carried by said supporting means in fixed spaced relation with respect to said cathode so as to move with said cathode upon adjustment of the position thereof, and additional electrodes coaxial with said hollow cylinder and supported conjointly therewith. 15

2. A cathode ray tube in accordance with claim 1, wherein said hollow cylinder is fixed to supporting discs carried by supporting rods which serve to align the cathode with respect to other electrodes of the tube. 20

3. A cathode ray tube in accordance with claim 1, wherein said cylinder is carried by a disc and said diaphragm electrode has a deformable lug which is bent in the form of a loop and attached to said disc to hold said electrode against displacement, the size of said loop being sufficient to permit longitudinal adjustment of said insulating supporting means within said hollow cylinder. 25

4. A cathode ray tube comprising a body of insulating material having a metallic tube centrally positioned therein, a heating coil positioned within said tube, a closure for the end of said tube forming an emitting surface, said body of insulating material having a recess forming an opening around said middle tube, and a control electrode comprising a metallic diaphragm having a central opening therein supported by the end of said insulating body and a hollow cylinder slidably enclosing said insulating body in tight frictional engagement to hold said body in a fixed position. 40
